UNITED STATES PATENT OFFICE.

JAMES G. ALLEN, OF DETROIT, MICHIGAN, ASSIGNOR TO ALLEN SCREEN COMPANY, OF DETROIT, MICHIGAN, A CORPORATION OF MICHIGAN.

WINDOW SCREEN.

Application filed July 18, 1921. Serial No. 485,482.

To all whom it may concern:

Be it known that I, JAMES G. ALLEN, a citizen of the United States of America, residing at Detroit, in the county of Wayne 5 and State of Michigan, have invented certain new and useful Improvements in Window Screens, of which the following is a specification, reference being had therein to the accompanying drawings.

10 In my Patent No. 1,214,494, granted Feb. 6, 1917, there is disclosed a window screen having a collapsible or foldable frame which permits of the screen being rolled whereby the entire structure will occupy a 15 comparatively small space when not in use.

This invention relates to a rigid window screen frame, in contradistinction to the collapsible frame of my prior patent, and this invention aims to furnish such a frame with 20 novel means for detachably retaining it within the window frame, so that the screen may be easily and quickly removed, particularly during inclement weather or during winter.

25 My invention further aims to provide a window frame screen that may be adjusted similar to a sash and locked in a lowered or closed position.

The construction entering into my invention will be hereinafter described and then claimed, and reference will now be had to the drawings, wherein—

30 Figure 1 is an elevation of the inner side of a portion of a window frame provided with a screen in accordance with this invention;

Figure 2 is a vertical cross sectional view taken on the line II—II of Fig. 1;

Fig. 3 is a front elevation of a window 40 screen;

Fig. 4 is a cross sectional view of the frame taken on the line IV—IV of Fig. 3;

Fig. 5 is an enlarged cross sectional view taken on the line V—V of Fig. 1, and

45 Fig. 6 is an enlarged horizontal sectional view taken on the line VI—VI of Fig. 1.

In the drawing, there is shown a portion of a window having a sill 1, stiles 2, strips 3, and an upper sash 4 having a meeting rail

50 5. The upper sash 4 is slidable between the strips 3, in the usual manner, and the lower sash has not been shown in order to more clearly show my wire screen in the window frame.

55 The window screen comprises a rectangu-

lar frame having side rails 6, a top rail 7, and a bottom rail 8, said rails having the ends thereof suitably joined to provide a rigid frame to which may be suitably connected the marginal ends of a wire screen 9. 60 This wire screen may be of the usual interwoven wire fabric adapted to exclude flies and other insects, and the edges of the screen may be connected to frame rails by beads 10 or other fastening means. In some instances glass may be substituted for the screen 9.

The side rails 6 of the screen frame are provided with longitudinal recesses 11 to receive side flanges 12 of channel shaped retaining members 13, said retaining members corresponding in length to the frame rails 6. The retaining members 13 may be shifted on the rails 6 to increase or decrease the overall width of the screen frame and holding 75 the retaining members 13 normally extended are flat springs 14 arranged in the upper and lower ends of the retaining members and connected to the frame rails 6, as best shown in Fig. 3.

To prevent the retaining members 13 from being completely shifted off of the rails 6 and at the same time afford convenient means of retracting the retaining members 13, finger pieces 15 are attached to one of the flanges 80 12 of each retaining member contiguous to the upper and lower ends thereof. The finger pieces 15 are slidable in cut away portions of the side rails 6 and said finger pieces have loop or stop portions 16 which abut the edges of the rails 6 and limit the outward movement of the finger pieces 15 and the retaining members connected thereto. The loop or stop portions 16 of the finger pieces 15 can be gripped when it is 90 desired to retract the retaining members 13 to remove one or both edges of the screen from the window frame, it is through the medium of the retractable retaining members 13 that the wire screen may be completely removed from the window frame.

Suitably attached to the opposed strips 3 of the stiles 2 are channel guides 17 which extend from the sill 1 towards the top of the window frame and to a sufficient height to permit of a wire screen being raised relative to the sill 1. The retaining members 13 are adapted to slide in the channel guides 17 and to facilitate moving the wire screen the bottom rail 8 has a suitable handle 18. The 100 105 110

handle 18 and the loop or stop portion 16 of the finger pieces 15 are within the screen frame and will not interfere with the operation of a lower sash within the window frame.

In order that the window screen may be locked in a lowered position, the retaining members 13, adjacent the lower ends thereof, have apertures 19 adapted to engage 10 studs 20 carried by the channel guides 17. The retaining members 12 will readily snap into engagement with the studs 20 and said retaining members may be retracted when it is desired to adjust the window screen. 15 Such locking means for the window screen may be used at one or both sides thereof and throughout the length of the channel guides 17 so that the window screen may be locked in a position to which it is adjusted.

20 To prevent flies or other insects from passing between the wire screen and the meeting rail 5 of the upper sash 4, particularly when such space exists between the meeting rail 5 and the top rail 7 of the window screen, said 25 top rail is provided with a transversely disposed wiper strip 21 which is secured to the top rail 7 and bears against the pane of the top sash 4. This wiper strip may be made of rubber, felt or a resilient material.

30 It is thought that the utility of the screen will be apparent without further descrip-

tion, and while in the drawing there is illustrated a preferred embodiment of my invention, it is to be understood that the structural elements are susceptible of such changes as 35 fall within the scope of the appended claims.

What I claim is:—

1. The combination of a window frame, channel guides therein, a screen frame, channel shaped retaining members slidably carried by said screen frame and slidable in said channel guides, said retaining members having openings adjacent the lower ends thereof, finger pieces attached to flanges of said retaining members adapted for shifting said retaining members to remove said screen frame from said window frame, and studs carried by said channel guides and adapted to extend into the openings of said retaining members. 40

2. The combination set forth in claim 1, wherein said finger pieces include stops adapted to engage the inner edges of the screen frame and limit the outer movement of the retaining members. 45

50 In testimony whereof I affix my signature in presence of two witnesses.

JAMES G. ALLEN.
